Frank A. Cutler,

ATTORNEY.

UNITED STATES PATENT OFFICE.

HERMAN R. HARRIGAN, OF HOLYOKE, MASSACHUSETTS, ASSIGNOR TO AMERICAN WRITING PAPER COMPANY, OF HOLYOKE, MASSACHUSETTS, A CORPORATION OF NEW JERSEY.

METHOD OF AND MEANS FOR EMBOSSED PAPER.

1,388,641.

Specification of Letters Patent. Patented Aug. 23, 1921.

Application filed April 9, 1919. Serial No. 288,704.

To all whom it may concern:

Be it known that I, HERMAN R. HARRIGAN, a citizen of the United States of America, and a resident of Holyoke, in the county 5 of Hampden and State of Massachusetts, have invented certain new and useful Improvements in Methods of and Means for Embossing Paper, of which the following is a specification.

10 My invention relates to improvements in methods of and means for embossing paper, and consists essentially in subjecting the paper to ground-work or background pressure on both sides, while at the same time 15 permitting the other portions of said paper to remain uncompressed, and thus leaving the pattern standing out on both sides, the outline on one side exactly coinciding with that on the other side; and of means where- 20 with to carry out the process briefly de- 25 scribed above, or, in other words, compres- 30 sion members having the pattern cut, en- 35 graved, or otherwise indented in their ad- 40 jacent surfaces and exactly alike relatively, 45 so that the portions of the paper compressed by and between said members are diametri- 50 cally opposite to each other, and the portions of the paper which are not compressed, but project into the indented portions of said 55 members, are diametrically opposite to each other, all as hereinafter set forth.

Heretofore paper has been embossed by subjecting it to the action of male and female compression members, or compressing 35 it between linen or other fabric. In the first of these cases the pattern is in offset relationship on the two sides of the paper, and, furthermore, the outline of the pattern is too sharp and harsh and so lacks the pleasing and artistic effect that it is desired to obtain; while in the second of these cases much expense is involved, the patterns are necessarily limited, and the pattern in any given example is also to some degree in off-set re- 45 lationship on the two sides of the paper. The primary object of my invention is, therefore, to produce a method of and means for expeditiously and economically embossing paper and embossing it so that both sides 50 are alike, that is to say, so that the outline of the pattern on one side of the paper exactly coincides in position and relatively with the outline of the pattern on the other

side, there being in fact but one pattern which has absolutely the same appearance on 55 both sides of the paper.

A further object is to provide a method of and means for producing embossed paper or embossing paper in such a manner that the sharpness of the pattern is eliminated 60 and replaced with a less severe or acute outline, or with an outline which is softened or toned down, so to speak, and, therefore, much more pleasing to the eye and better adapted for writing and printing paper 65 when applied to such paper.

Other objects and advantages will appear in the course of the following description.

I attain the objects and secure the advantages of my invention and carry out the 70 method by the means illustrated in the accompanying drawings, in which—

Figure 1 is an end elevation of the rolls with which I prefer to carry out my method, only segments of such rolls being shown, 75 and the pattern indentations therein, together with the paper associated with said rolls, being on a greatly enlarged and even exaggerated scale, the better to illustrate the invention; Fig. 2, a plan of a piece of paper 80 embossed by said rolls, also on the same enlarged or exaggerated scale; and, Fig. 3, an end elevation, exaggerated as in the other views, of another means whereby the desired results may be obtained.

85

Similar characters of reference designate similar parts throughout the several views.

With this invention I am able to give any desired special finish to paper on both sides, such as a fabric finish, for example, or a 90 finish in imitation of leather—any finish, in fact, the design of which can be engraved on the compression members. I here show a simple parallel-line finish or embossing.

In Fig. 1 two rolls 1 are represented. 95 These rolls are substituted for those usually employed in an embossing machine. They must be very rigid so that they cannot spring, and, of course, it is necessary that the same be maintained in perfect alinement. 100 Engraved in the peripheral surface of each roll 1 is the pattern, the engraving in one roll being identical with that in the other roll, such engraving in this case consisting of parallel grooves 2 which are spaced 105 equidistant from each other. The rolls 1

are mounted and driven so as to locate any pair of adjacent, associated, or companion grooves 2, when they arrive in the vertical plane of the axes of said rolls, it being understood that the latter are located with their axes in the same vertical plane, diametrically opposite to or in line with each other.

In the old method and means one of the rolls has a depressed pattern, as in the present case, but the other roll has a raised pattern to press the paper into the depressions in the first roll.

A piece of paper is represented at 3. This piece may be a part of a sheet or a part of a roll, it being immaterial whether the paper be fed to the rolls 1 in sheets or from a roll of the same.

The rolls 1 are so positioned relatively that the space between them is less than the thickness of the paper 3. It is now plainly to be seen that, when the rolls 1 are set in motion and caused to revolve in opposite directions and the paper is fed between them, said paper is compressed by those portions of said rolls which are between the grooves 2, while the portions of said paper that pass between the open mouths of said grooves, which latter are diametrically opposite to each other adjacent to the points of greatest compression, are left in their original state or without being compressed. These non-compressed portions, represented at 5, outline the pattern and constitute the embossing. They are the same on both sides of the paper, both in shape and location. And their edges are not too abrupt or sharp, but are tapered or curved so as to unite the pattern with the background in such a way as to produce a graceful appearance and harmonious effect. Such effect is due partly to the shape of the edges of the grooves 2, which may be rounded more or less, and partly to the method by which the work is done. The compressed background is indicated by the numeral 4, and the raised pattern by the numeral 5 as previously intimated.

An example showing one side of the embossed paper, or of the paper as it appears after passing between the rolls 1, is represented in Fig. 2.

In place of the rolls 1 it may be possible to employ plates 6—6 having therein the grooves 2 in diametrical juxtaposition, as shown in Fig. 3. With this means of compression the paper 3 is inserted between the plates 6, and the latter are pressed together to compress said paper and form the background 4, at the same time leaving the pattern 5 which is made up or consists of the uncompressed portions of the paper. The means just described for giving effect to my method is not believed to be nearly so prac-

tical or efficient as the first, but might be useful in some cases and with some papers.

The embossing is done on paper which is in a dry state, that is to say, on paper that has passed through the process of manufacture.

The compression members or elements are usually heated for the work of embossing.

The method in detail will be fully understood from the foregoing description of the compression elements and the explanation connected therewith.

Some minor changes in or departures from the details herein set forth may be made without violating the spirit of my invention or exceeding the scope of what is claimed.

What I claim as my invention, and desire to secure by Letters Patent, is—

1. The method of embossing paper consisting in passing the paper between compression rolls which have therein continuous indentations parallel with the axes of said rolls, and arranged to leave uncompressed diametrically opposite portions of the paper on opposite sides thereof, the unindented portions of said rolls penetrating the paper without meeting, and the indented portions of said rolls at their deepest parts contacting with the normal exterior surfaces of the paper.

2. Means, for embossing paper, comprising rolls having in their peripheral surfaces continuous indentations parallel with the axes of said rolls, and so arranged that, when any two adjacent indentations in both of said rolls arrive in a plane common to the axes of said rolls, said indentations are diametrically opposite to each other, the bite between the unindented portions of the rolls being less than the thickness of the paper passed therebetween, and the bite between the deepest parts of the indented portions of the rolls being approximately equal to the thickness of said paper.

3. Means, for embossing paper, comprising rolls having in their peripheral surfaces continuous indentations which are parallel with the axes of said rolls and curved in cross section, and which are so arranged that, when any two adjacent indentations in both of said rolls arrive in a plane common to the axes of said rolls, said indentations are diametrically opposite to each other, the bite between the indented portions of the rolls being less than the thickness of the paper passed therebetween, and the bite between the deepest parts of the indented portions of the rolls being approximately equal to the thickness of said paper.

HERMAN R. HARRIGAN.
